UNITED STATES PATENT OFFICE.

HAROLD H. CLARK, OF SPRINGFIELD, MASSACHUSETTS.

NONARCING SWITCH.

Application filed December 4, 1919. Serial No. 342,417.

To all whom it may concern:

Be it known that I, HAROLD H. CLARK, a citizen of the United States of America, residing at Springfield, in the county of

5 Hampden and State of Massachusetts, have invented certain new and useful Improvements in Nonarcing Switches, of which the following is a specification.

This invention relates to improvements in 10 non-arcing switches and, more particularly, to switches of this character which are suitable for use in localities, such as mines, where inflammable gases are prevalent, for breaking circuits which carry relatively 15 heavy currents. The invention aims to provide a switch which may be used with safety in such localities and, in practical effect, be explosion proof.

The broad object of this invention is to 20 provide in a switch, means, in the character of a liquid conductor, which, when the switch is closed, forms with the switch blade a divided circuit, and which when the switch is first opened carries all the current 25 for a momentary interval (thereby preventing an arc between the blade and its jaw) and later breaks the circuit out of contact with the surrounding atmosphere by displacement of the conductor.

30 Another object of the invention is to provide a switch, which includes a blade pivoted to swing from an upper and closed position to a lower and open position and a chambered member carried by the blade and 35 containing a liquid conductor, such as mercury, which when the blade is in closed position forms with the blade a divided circuit, and when the blade is in open, but still in generally upright position, carries the current until further movement toward its 40 lower position, wherein the liquid conductor is displaced to break the circuit in the chambered receptacle.

Another object of the invention is to 45 provide a single pole, double break, switch of the pivoted knife blade type, wherein the jaws are electrically connected together and the blades carry a chambered member containing a liquid conductor, such as mercury, 50 which when the blades are in generally upright position forms a shunt electrical con-

nnection between the blades, such connection being broken by displacement of the mercury when the blades are moved to or toward their lower position.

55 Another object of the invention is to provide in a switch of the general character defined, means for preventing the maintenance of arcs to and from the mercury after it has been displaced to break the circuit, 60 since such arcs would cause the undesired production of mercury vapor and thereby provide a relatively good conductor across the terminals of the switch.

65 Another object of the invention is to provide, in a non-arcing switch of the character described, generally improved mechanical structure.

70 Other objects and advantages will appear in the following description and in the illustrative embodiment of the invention in the accompanying drawings, in which:

75 Fig. 1 is an elevational view partly in section of a single pole switch embodying the invention,—the switch being shown by full and dotted lines in closed and open positions,

respective;

Fig. 2 is a sectional plan view taken on the line 2—2 of Fig. 1;

Fig. 3 is a fragmentary sectional plan 80 view taken on the line 3—3 of Fig. 1;

Fig. 4 is an elevational view partly in section of a double pole switch embodying the invention; and

Figs. 5 and 6 are elevational views partly 85 in section showing modifications.

Referring to these drawings; the invention is capable of application to various types of switches in which there is a pivoted switch member movable from a generally upright position to a generally depending position. The invention is also capable of application to any switch wherein the circuit closing member is so movable as to cause a substantial displacement of a 90 liquid conductor, such as mercury, which is contained in a member movable by the switch member. The invention has been illustrated as embodied in the two main types of switches,—namely, the single pole and double pole type but may be embodied 95 in various other types of switches than those 100

illustrated, for the details of the switch structures shown may be varied in numerous particulars and still embody the invention.

5 Referring more particularly to Figs. 1, 2 and 3, the invention as embodied in a switch of the single pole type, will first be described. A represents the base of the switch, which is formed of suitable insulating material, and secured to this base in laterally spaced relation are pairs of brackets b, each pair being adapted to receive between them a switch blade c, which is pivotally connected to the brackets at d. The blades 10 c are connected at their upper ends by a bar e of insulating material and, upon the bar, a suitable handle f is provided. Each blade c, when in closed position, is received between a pair of jaws g and such jaws are 15 electrically connected together by a bar 5. The brackets b, b, form the terminals of the switch, which is thus of the single pole, double break type.

A block 6 of suitable insulating material, 20 such as fibre or the like for example, is supported by the blades c. Preferably, as shown, the block is of rectangular shape, and of such size as to fill the space between blades c, for the block, as will appear, is chambered 25 to afford a long and circuitous path and to obtain a path of the desired length, it is generally desired to make the block as large as possible. The block 6 is provided with a plurality (three, as illustrated) of vertical 30 passages 7 therein, which are preferably circular in cross section, and extend from the top of block 6 toward and closely adjacent the lower end thereof. The block 6 is further provided near its lower end with a 35 through horizontal passage 8, also preferably of circular cross section, which passage intersects all of the vertical passages.

Both ends of the passage 8 are closed by 40 closely fitting screws 9, suitable material being applied to the threads thereof, if necessary, to secure a tight and leak proof joint. The screws 9, as will appear, constitute electrodes and are electrically connected to the 45 adjacent blades c in any suitable manner, as by integral studs 10 which pass through the blades and are held thereto by nuts 11, thus serving also to support the block 6. Additional supporting connection between the 50 block 6 and blades c is afforded by screws 12 which pass through the blades and thread 55 into the block but do not enter any of the passages described.

The passages 7 are closed, and tightly 60 sealed, by screws 13, which, if necessary to provide additional effective volume for the 65 passages 7, may be cupped out as indicated at 14. Each passage 7, preferably, extends slightly below the passage 8 to form a seat 70 for, and receive, the circular base 15 of a

barrier member,—the barrier portion, indicated at 16 extending upwardly a substantial distance into its passage 7 and paralleling the switch blades c, to partition the passage. The bases 15 preferably closely fit their seats to prevent leakage from the 70 passage 8, and if necessary, may be additionally held to the block by screws 17. The 75 passages 7 and 8 are supplied, prior to the application of screws 13, with mercury, as indicated at m, and the amount supplied is 80 sufficient to entirely fill passage 8 and to fill passages 7 to a level above the tops of the barriers 16, when the switch is in closed position.

The particular form of single pole switch described is not necessarily essential. For example, the terminals of the switch might consist of the left hand bracket b and jaw g, the conductor 5 and the right hand jaw g being omitted and replaced by a conductor 85 18 on the back of base A, which conductor would directly connect the right hand bracket b to the left hand jaw g; as shown in Figure 5.

Moreover, the invention is not necessarily 90 confined to the use of the brackets b as terminals of the switch and may equally well be used with a switch of the type having two jaws for each blade. Thus, as shown in Fig. 6, the blade c pivoted at d to a bracket b, as described, is engageable with a second jaw g' as well as the jaw g described. The blade c is therefore entirely disconnected from the circuit when in open position. The member 6 may then be mounted centrally on blade c 95 and arranged to overlie the latter being mechanically but not electrically connected thereto by brackets 30. The electrodes 9 are arranged to separate blades 31, which are 100 arranged one on each side of blade c and are pivoted at 32 to brackets 33 to swing about the same axis as blade c. One bracket 33 is electrically connected by a strap 34 to jaw g' and the other by a strap 35 to jaw g.

105 Preferably, although not necessarily according to all features of the invention, metallic members, as rods 19, are secured in the passages 7 at points above the tops of barriers 16. The function of these rods will 110 be explained in the description of the operation of the switch.

115 The invention, as embodied in a double pole switch, will now be described with reference to Fig. 4. Two blades c, pivoted at d to brackets b on base A and engageable 120 with jaws g are provided, as heretofore described, but the jaws g are not electrically connected together as before. Two of the 125 chambered members 6 are provided, each similar in construction to that one described in connection with Fig. 1, and arranged one above the other. One electrode 9 of the upper member 6 is connected to the

right hand blade *c* but the other passes through the other blade *c* and is insulated therefrom by a bushing 20. The last-named electrode is connected to an auxiliary conducting blade 21 pivoted at 22 to a bracket 23 to swing about the same axis as blade *c* and mechanically connected thereto, as by a cross piece 24 of insulation. The bracket 23 is electrically connected to the right hand 5 jaw *g*, as by a strap 25 on the back of base A. Thus, a divided circuit is formed between the right hand bracket *b* and the corresponding jaw *g* by the right hand blade *c* and by the mercury contained in the upper member 10 15 20 25 30 35 40 45

6. The construction described is generally analogous to that shown in Fig. 1. Similarly, the left hand electrode 9 of the lower member 6 is electrically connected to the left hand blade *c* while the other electrode is connected to an auxiliary blade 26, pivoted similarly to blade 21 to a bracket 27, which is electrically connected to the left hand jaw *g* by a strap 28 on the back of base A. Thus, a divided circuit is formed between the left hand bracket *b* and the corresponding jaw *g* by the left hand blade *c* and by the mercury contained in the lower member 6.

The switch, illustrated in Fig. 1, affords two paths for the current when it is in closed position. One of these paths is of extremely low, and almost negligible, resistance since it includes the metallic blades *c*, the jaws *g*, and the metallic bar 5, all as usual, of ample cross section. The other path, hereinafter termed the shunt path, since in conjunction with the path described it forms a divided circuit, is of considerably higher resistance since the conducting material is largely mercury. Thus, when the switch is in closed position, some current constantly travels along the shunt path but, due to the relatively high resistance of this path, the amount of current flowing is very small,—the main path including blades *c* and bar 5 affording practically a short circuit.

Upon an opening of the switch, sufficient to disengage blades *c* from jaws *g*, the circuit is not immediately broken, but all the current is diverted to the described shunt path. 50 55 60 65 70 75 80 85 90 95 100 105 110 115 120 125

The resistance of such path, although considerably higher than that of blades *c*, is nevertheless not high enough to produce a drop of potential across the blades *c* (even when carrying heavy currents) sufficiently large to cause an arc between the jaws *g* and blades *c*. At least no spark, of sufficient intensity to be dangerous, occurs between the blades *c* and the jaws *g*, when the former is disengaged from the latter. This result is attained by providing a large cross sectional area for the conducting path through the mercury. For example, the resistance of the shunt path may well be held to a few hundredths or even a few thousandths of an ohm

so that even when heavy currents, as for example, five hundred amperes, are carried, the drop of potential may be held to a few volts, notwithstanding the fact that the resistance of mercury is approximately sixty times that of copper.

The current is carried by the shunt path only for a momentary interval and, consequently, undue heating does not occur. The blades, when disengaged from jaws *g*, are swung downwardly into the dotted line position in a very short interval and the time during which the current traverses the shunt path is so extremely short as to be for all practical purposes negligible. Upon a movement of the blades *c* into the dotted line position, the mercury is displaced in member 6 and falls away from the electrodes 9 and barriers 16. Thus the circuit through the shunt path is broken out of contact with the surrounding atmosphere and, such arcing as occurs, cannot work damage. The long circuitous path from one electrode 9 to another around the several barriers insures against the maintenance of an arc between the electrodes.

To guard against the possibility of prolonged production of mercury vapor, which, of course, is a good conductor and might permit an arc to be maintained between the electrodes 9, the rods 19 or other equivalent means, are provided. Mercury vapor would be produced only by an arc passing along one side of a barrier 16 to into and through the mercury and back along the other side of the barrier. The metallic rods 19, by their interposition between the top of barriers and that end of member 6, which contains the mercury when the switch is in open position, short circuits any such arcs and prevents them from travelling beyond into and through the mercury.

The operation of the switches shown in Figs. 4 and 5, is analogous and will readily be understood from the foregoing description.

The invention has been disclosed herein for illustrative purposes, in an embodiment, at present preferred, and in detailed variations. It is recognized, however, that modifications may be made in the structures herein disclosed, having for their object the use of the invention in a form differing specifically from that disclosed. It is therefore desired to have the scope of the invention defined by the appended claims, interpreted by the spirit of the disclosure rather than by the letter of the exact forms disclosed.

What I claim is—

1. In combination with a switch, having a movable circuit controlling member and a device with which such member may be engaged to close the circuit and disengaged to open the circuit, a movable chambered

- member operable by movement of the first-named member and containing a liquid conductor, and means cooperating with such conductor to establish a shunt electrical connection between the first-named member and said device when the former engages the latter.
2. In combination with a switch, having a movable circuit controlling member and a device with which such member may be engaged to close the circuit and disengaged to open the circuit, a movable member operable by movement of the first-named member, a pair of spaced electrodes therein, means electrically connecting one electrode to the first named member and the other to said device when the former and latter are engaged, a passage provided in the second member, and a liquid conductor partially filling such passage and electrically connecting said electrodes when said device is engaged by the first-named member, the latter being movable to displace said conductor in the second member to break the connection between said electrodes and provide a circuitous non-conducting path from one to the other.
3. In combination with a switch, having a movable circuit controlling member and a device with which such member may be engaged to close the circuit and disengaged to open the circuit, a member movable by the first-named member, a pair of spaced electrodes therein, means electrically connecting one electrode to the first-named member and the other to said device when the former and latter are engaged, a passage provided in the second member, a liquid conductor partially filling such passage and electrically connecting said electrodes when said device is engaged by the first-named member, the latter being movable to displace said conductor in the second member to break the connection between said electrodes and provide a circuitous non-conducting path from one to the other, and means in said passage tending to prevent the prolonged maintenance of an arc between an electrode and the liquid conductor when the latter is in displaced position.
4. In a switch of the knife blade type, having a jaw and a pivoted blade engageable with said jaw, a movable chambered member operable by movement of said blade, a liquid conductor in said member, and means cooperating with said conductor to establish a shunt connection between said jaw and blade when the latter engages the former, said member being movable on an opening of the blade to displace said conductor and break said connection.
5. A switch comprising, two pivoted blades, the pivots of said blades forming the terminals of the switch, a jaw for each blade, an electrical connection between said jaws, a chambered member movable by the blades, and a liquid conductor in said member forming an electrical connection between the blades when the latter are in generally upright position, said member being movable into substantially inverted position to break the last-named connection by displacement of said conductor.
6. A switch comprising, two pivoted blades, a jaw engageable by each blade, means electrically connecting said jaws, a member movable on disengagement of said blades and jaws and provided with a circuitous passage extending between the blades, and a liquid conductor partially filling said passage and forming an electrical connection between the blades when the latter are in generally upright position, said member being movable into substantially inverted position to break the last-named connection by displacement of said conductor.
7. In combination with a switch having two pivoted knife blades, a member carried by and interposed between the blades, a passage extending across said member, electrodes closing the ends of said passage and each connected to the adjacent blade, a series of branch passages leading from the first-named passage, barriers extending across the latter and into the branch passages, and a liquid conductor filling the first-named passage and the branch passages to points beyond the ends of the barriers when the blades are in generally upright position, said blades being movable to substantially invert said member and displace said conductor into the branch passages and out of contact with said barriers.
8. In combination with a switch, having two pivoted blades, a member of insulating material carried by and interposed between the blades, a series of holes extending from one end of the member toward the other end thereof, a transverse passage intersecting all said holes, an electrode in each end of said passage, a series of barriers each having a circular base seated in the base of one of said holes and a portion extending across said passage and into the holes to partition them, and mercury within said member and arranged to fill said passage and fill said holes to a level above the barriers when the blades are in substantially upright position.
9. A switch mechanism, comprising, two spaced contacts, means providing two multiple electrical connections between said contacts and including a member in each connection movable to interrupt its connection, one of said connections being of relatively low resistance and the other of higher resistance, the movable member in the connection of higher resistance having a substan-

tially air-tight chamber, and a liquid conductor in such chamber and forming a part of the high resistance connection.

10. A switch mechanism, comprising, two spaced contacts, means providing two multiple electrical connections between said contacts and including a member in each connection movable to interrupt its connection, one of said connections being of relatively low resistance and the other of higher re-

sistance, the movable member in the connection of higher resistance having a substantially air-tight chamber, a liquid conductor in such chamber and forming part of the high resistance connection, and mechanical connections between said members to insure that the low resistance connection will be interrupted before the connection of higher resistance and closed after the latter.

HAROLD H. CLARK.
